COLLAPSIBLE MODEL FORM

Joseph Kroll, Brooklyn, N. Y.

Application November 3, 1943, Serial No. 508,795

4 Claims. (Cl. 223—68)

This invention relates to garment forms and more particularly to a type having collapsible parts for adjusting the sections of which said forms are composed for the purpose of adjusting said form to the size and cut of the garments to be supported thereupon as well as to facilitate the removal of said garment therefrom after the same has been assembled and without danger of tearing the same.

It is accordingly the primary object of this invention to achieve the above mentioned purposes by providing a form with retractile and extensible side and shoulder portions which portions are hinged at their lower ends to said form and shaped for telescoping lateral movement inwardly and outwardly therefrom through the medium of a link and screw mechanism arranged within said form and adjustably by hand manipulation externally of said form.

Other objects of the invention are, the provision of mechanism in a form of the character referred to which is solid and positive in operation, simplified in structure and of the requisite degree of strength, which can be readily assembled inside the form, to provide improved means for guiding and controlling the various movement of the adjustable parts of the mechanism, and which can be manufactured at a minimum cost.

Another object of this invention is to provide an apparatus which may be used with all kinds of forms, such as men's coat forms, ladies' dress, suit, jacket and sweater forms.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Figure 1 is a front view of the collapsible form with parts broken away.

Figure 2 is a side view of the same.

Figure 3 is a sectional view taken on line 3—3, Figure 1.

Figure 4 is an elevational detail view of the hinge pin.

Referring to the drawing in detail, 10 denotes a garment form made by molding any suitable material such as papier-mâché, or by stretching fabric on a suitable frame, to form the hollow body portions 11 and 12 above and below the waist respectively in a unitary structure having shoul-

der openings 13 which include a part of the bust portion 14 of the form 10. It is to be understood that the garment form may be given a variety of shapes to thereby provide forms for men's, ladies' and children's garments, and that the type of form shown in the drawing is utilized for purposes of illustration only.

To complete the form 10, there is provided a pair of shoulder portions 15 shaped to fit the shoulder openings 13. The lower edge of the shoulder portion 15 and the shoulder opening 13 are straight and horizontal, and secured to the inside lower edge portion of the shoulder portion 15 is a hinge element 16 mating with a complementary hinge element 17 secured to the inside portion of the body portion 12, both hinge elements being pivotally connected together by a readily removable hinge pin 18. The hinge pin 18 is constituted by a cylindrical pin or rod comprising a shank 19 formed at one end with an eye 20 and slotted at its other end as at 21 to receive one end of a lock bar 22 pivotally held therein by a pivot pin 23, the lock bar having a width not greater than the diameter of the hinge pin. Thus, to insert the hinge pin 18 in position the lock bar 22 is moved into coextensive relation with the shank 19, and after insertion the lock bar 22 is moved down to thereby lock the hinge pin in place as clearly shown in Figure 2; and in a like manner the hinge pin 18 may be readily removed to effect removal of a shoulder portion 15 when necessary to permit of adjustment or repair of the mechanism within the form 10 as will be herein-after described.

The form 10 is closed at its bottom by a panel 25 through which extends a tubular standard 26 rigidly secured at its lower end to a base 27 mounted on casters 28. The standard 26 extends upwardly into the form 10 in the vertical axis thereof, and its upper end terminates in a flanged head 29 lying somewhat above the plane of the hinge axis, see Figure 1. Fitted in the flanged head 29 is a set screw 31, and telescopically arranged in the tubular standard 26 is a rod 32, which is held in adjusted position relative to the standard 26 by said set screw 31, the position of the rod 32 determining the height of the form 10 relative to its base 27 as will be herein-after described.

The form 10 includes a neck portion 35 closed by a collar 36 rigidly secured to said neck portion, and provided with an axial opening 37. Extending through said opening 37 is a sleeve 38 which surrounds the upper end portion of the rod 32. The rod 32 extends beyond the upper end of

said sleeve 38. A knob 40 has threaded engagement with the end of the rod 32, said knob including a cylindrical cap 41 arranged to seat in concentric relation over the extended end of the sleeve 38 and to abut the collar 36. A set screw 42 on the cap 41 secured the knob in adjusted position on the end of the sleeve 38 and rod 32. Fitted on the threaded end 43 of the rod 32 is a wing-nut 44 which serves to lock the rod 32 and knob 40 in their adjusted position.

The sleeve 38 is externally threaded at its lower end as at 46, the terminal end of the sleeve 38 seating on a washer 47 positioned on the rod 32 and held in place thereon by a pin 48. A cross-head 50 comprising a cylindrical internally threaded boss 51 and a pair of diametrically opposed arms 52 is seated on the washer 47, the threaded end 46 of the sleeve 38 having threaded engagement with the boss 51. Seated on the terminal end of each of the cross-head arms 52 is one end of a link 54 pivotally held thereto by a pin 55 and cotter-pin 56, as clearly shown in Figure 1. Each link 54 is provided at its other end with an eye 57 connected to an eye-bracket 58 which latter is secured in any desired manner to a shoulder portion 15. Provided on the boss 51 is a set screw 59 which is adapted to clamp the cross-head 50 in adjusted position on the sleeve 38, if so desired.

It will be apparent that the links 54 connecting the shoulder portions 15 to the cross-head 50 will hold the latter from turning. Thus, rotation of the knob 40 will effect rotation of the sleeve 38 such as to impart vertical movement to the cross-head 50, either up or down, depending on which direction the knob is turned. In the position of the parts shown in Figure 1, the cross-head 50 is in its lowermost position and the shoulder portions 15 are moved outwardly to their maximum extent. Inward movement, i. e., collapsing movement of the shoulder portions 15 is effected by rotation of the knob 40 in the appropriate direction so as to cause upward movement of the cross-head 50 on the sleeve 38. Where it is desirable to lock the cross-head 50 in any selected adjusted position of the shoulder portions 15, the set-screw 59 is set down, this being accomplished by first detaching a hinge pin 18 to permit partial removal of a shoulder portion 15 from the shoulder opening 13 so as to permit access to the interior of the form.

Having thus described the invention, what is claimed is:

1. A garment form comprising a hollow body portion having shoulder openings, shoulder portions hinged at their lower ends in said openings for retractile movement from a maximum extended position to a closed position, a vertical rod extending axially through said garment form, a tubular standard mounted on a base for telescopically supporting said rod, means on said standard for locking said rod in adjusted position, said rod extending upwardly beyond said

form, manual manipulative means on said rod externally of said form, and means within said form mounted in concentric relation to said rod and actuated by said manual manipulative means and movable vertically relative to said rod and connected to said shoulder portions to simultaneously move the same to a selected adjusted position.

2. A garment form comprising a hollow body portion having shoulder openings, a shoulder portion fitted to each shoulder opening, a hinge comprising two hinge elements connecting the lower end of each shoulder opening to said body portion, and a readily detachable hinge pin joining said hinge elements including a pivoted locking bar so arranged when said hinge pin is in place as to prevent accidental removal thereof, and manually actuated means connected to said shoulder portions to simultaneously move the same to a selected adjusted position.

3. A garment form comprising a hollow body portion having shoulder openings, a shoulder portion fitted to each shoulder opening, a hinge comprising two hinge elements connecting the lower end of each shoulder opening to said body portion, and a readily detachable hinge pin joining said hinge elements including a pivoted locking bar so arranged when said hinge pin is in place as to prevent accidental removal thereof, a vertical rod extending axially through said garment form, a standard mounted on a base for supporting said rod, and manually actuated means movable vertically relative to said rod and connected to said shoulder portions to simultaneously move the same to a selected adjusted position.

4. A garment form comprising a hollow body portion having shoulder openings, a shoulder portion fitted to each shoulder opening, a hinge comprising two hinge elements connecting the lower end of each shoulder opening to said body portion, and a readily detachable hinge pin joining said hinge elements including a pivoted locking bar so arranged when said hinge pin is in place as to prevent accidental removal thereof, a tubular standard mounted on a base, a rod extending axially through said form and telescoped in said tubular standard, means on said standard for locking said rod in adjusted position relative thereto, the upper end of said rod extending upwardly through the neck portion of said form, a sleeve surrounding the upper end portion of said rod, a knob on the upper end of said sleeve arranged externally of said form, means on said rod end for locking said knob in adjusted position, means on said knob for locking the same to said sleeve, a cross-head having threaded engagement with the lower end of said sleeve and link means connecting said cross-head and shoulder portions, whereby rotation of said sleeve in one direction or the other will impart raising or lowering of said cross-head to effect a lateral inward or outward movement of said shoulder portions.

JOSEPH KROLL.
